UNITED STATES PATENT OFFICE.

VICTOR R. DESPARD, OF VALPARAISO, INDIANA, ASSIGNOR TO MCGILL MANUFACTURING COMPANY, A CORPORATION OF INDIANA.

MULTIPLE-SERIES SWITCH.

Application filed October 16, 1925. Serial No. 62,833.

My invention relates to means for connecting a plurality of circuits each including an electrical device either in series or in parallel, and more particularly to a multiple-series switch for accomplishing this purpose.

It is a purpose of my invention to provide means for connecting a pair of electrical devices with a source of current supply either in series or in parallel, said means comprising switching means connected with said source of current supply and said electrical devices in a peculiar manner whereby simplicity of operation and compactness results. The electrical devices are preferably duplicate lamps or substantially duplicate lamps and means is preferably provided that connects one terminal of each of the lamps permanently with the source of current supply. and switching means is provided that has contacts connected with the source of current and with both terminals of both of the lamps and has also contacts cooperating with said first mentioned contacts to connect the other terminals of each of the lamps with the source of current supply or with each other to illuminate said lamps substantially equally, both when bright and dim. This is particularly desirable when the lamps are arranged in a cluster, such as in a reading lamp or floor lamp or a bracket fixture where it is desirable that the same illumination be obtained from the two lamps at all times to obtain a better appearance for the lamp or other lighting fixture and to obtain a more uniform illumination therefrom than would otherwise be possible. In other words, the lamps are connected in parallel when bright and are of substantially equal brightness and are connected in series when dimmed to thus be again illuminated with substantially equal brightness.

It is a further purpose of my invention to provide a device for connecting the said electrical devices either in series or in parallel comprising a pair of contacts each connected with a conductor leading from a source of current supply and with a conductor leading to an electrical device and a second pair of contacts each connected with a conductor leading to one of said electrical devices and a movable member having contacts mounted thereon adapted to bridge said first mentioned contacts to connect said electrical devices with said source, either in

series or in parallel. Preferably, the movable contact member is rotatable and preferably, also, always rotatable in the same direction. In order to obtain the parallel and series connection in the simplest manner, one of the contacts of one pair is preferably provided with an extension so that the movable contact means will connect said extension with the other contact of the pair to make the series connection. The contacts on the rotatable member are preferably a pair of bridging contacts arranged on opposite sides of the center of rotation of said member so as to make the proper series and parallel connections in the simplest manner. The stationary contacts are also preferably arranged in pairs lying substantially diametrically opposite each other and the contacts on the movable contact member when the parts are in position to make the parallel or multiple connection preferably each bridge from one contact of one of the opposite pairs to a contact of the other opposite pair.

It is a further purpose of the invention to provide a multiple-series switch of the above mentioned character comprising a rotatable member that is adapted to assume a plurality of positions by a step by step rotation thereof. In the particular embodiments shown, the number of positions in one complete rotation of the device is six. These comprise three different positions, that is, the series of positions repeats itself in the course of the rotation of the rotatable member. In one of these positions, the electrical devices, such as the lamps associated with the switch, are connected in parallel, in another position they are connected in series and in the third position they are disconnected from each other so that no current flows through the same. In order to make a device of this character as compact as possible and to assure the user that the device will properly maintain its various contacting positions, the switch mechanism preferably comprises a body portion having ratchet teeth thereon. The rotatable member having the contact means thereon for completing the circuit is provided with means engaging said ratchet teeth so as to hold the parts in their respective positions to make the various connections desired. In order to make a device of this character of practical use, it is furthermore necessary

that the contacts engage and disengage quickly, accordingly, the device is so constructed that a snap action is obtained for the switching means.

5 In order to carry out these purposes in the most efficient manner with the least use of space, it has been found particularly desirable to make the body portion of the switch enclosing the movable parts of insulating material and to form faces thereon that provide the series of ratchet teeth whereby the snap action of the switch is obtained. The stationary contacts, connected as referred to above to the various devices associated with the 15 switch, have portions that preferably overlie certain of these faces and these faces are preferably arranged in an annular series around a central depression or recess within which the movable contact carrying means seats. 20 Said means preferably comprises a member of insulating material disk-like in form that nests in said recess with the bridging contact members mounted on the exposed face thereof, said contact members having extensions overlapping the periphery of the disk-like member so as to align with the stationary contacts as the movable contact member is rotated in its step by step movement, being guided in said movement by its 25 engagement with said recess. In order to obtain the desired snap action, resilient means is provided for holding the contacts on the movable member in engagement with the ratchet teeth or with the contacts there- 30 on, said resilient means being preferably mounted on an operating spindle or stem that is in operative engagement with the movable contact carrying member.

It is one of the important purposes of the 40 invention to provide a switch mechanism of the above mentioned character that is simple in construction and has a minimum number of parts. For this reason, the terminals to which the conductors leading from the 45 switch are connected are formed in one with the stationary contacts and the stationary contacts are preferably made as few in number as is possible to obtain the desired operation of the switch. For this reason, one of 50 said contacts in the preferred form is extended to overlie two of the ratchet faces so as to make it possible to obtain the series connection as well as the parallel connection with only four contacts. The stem or spindle for rotating the movable contact carrying member is preferably also connected with the device in the simplest possible manner, being merely flattened and extending into an elongated opening in the insulating 55 disk of the movable contact carrying member and being surrounded by a coil spring whereby the resilient action necessary to hold the disk in its proper position and obtain the snap action results. The movable contact carrying member is also made in

the simplest possible manner, in its preferred form being merely a disk of insulating material and having a pair of bridging contacts preferably of phosphor bronze secured thereto by means of a staple extending through paired openings in the insulating member and the contacts, said staple being made of a softer material such as brass to enable the movable contact member to be easily assembled. 75

The switch mechanism is preferably provided with a suitable cover plate which is provided on the insulating body portion and the stationary contacts are preferably provided with portions that are mounted between said insulating body portion and an insulating gasket below the cover plate to hold the same in position. The spring is also insulated from the contacts on the movable contact carrying member by an insulating washer mounted on the operating spindle. The stationary contacts are preferably so mounted that they align with openings extending through the insulating body portion whereby contact can be readily made therewith for testing purposes. This is particularly desirable because conductors or pigtail connections are provided on the terminals associated with the contacts in order to make the proper connections with the line and the lamps or other electrical devices. The provision of the openings for testing purposes makes it unnecessary to bare the ends of the wires forming the pigtail connections for testing purposes. 95 100

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims. 110 115

In the drawings:

Fig. 1 is a plan view of my improved switch, the conductors leading therefrom being partly broken away; 115

Fig. 2 is a side elevation thereof;

Fig. 3 is a plan view similar to Fig. 1 with the cover and the outer operating parts of the mechanism removed;

Fig. 4 is a section of the switch mechanism, a portion of the operating means being broken away, the section being taken on a line corresponding to the line 4-4 of Fig. 3; 120

Fig. 5 is an enlarged fragmentary section taken substantially on the line 5-5 of Fig. 3; 125

Fig. 6 is a perspective view of the movable contact carrying member;

Fig. 7 is a view partly in side elevation and partly in section thereof;

Fig. 8 is a diagrammatic view showing the 130

circuit connections for my improved switch mechanism whereby the series and parallel connections are obtained;

Fig. 9 is an elevational view showing my switching mechanism applied to an electrical fixture having two lamps associated therewith;

Fig. 10 is a section taken on the line 10—10 of Fig. 3;

Fig. 11 is a fragmentary perspective view of the operating spindle;

Fig. 12 is a plan view of the insulating disk mounted on said spindle;

Fig. 14 is a transverse sectional view of a modified form of my invention;

Fig. 15 is a section taken on the line 15—15 of Fig. 14; and

Fig. 16 is a section taken on the line 16—16 of Fig. 14.

Referring in detail to the drawings in the preferred form shown in Figs. 1 to 13 inclusive, my improved switch mechanism comprises an insulating body portion 20 which may be made of any suitable insulating material, but is preferably made of molded insulating material such as bakelite. Said body portion is provided with a cover plate 21 and an insulating gasket or washer 22 is provided between said cover plate and said body portion 20. The body portion 20

is provided with a substantially central preferably circular recess 23 formed in the material thereof adjacent which is an annular shoulder 24 which is arranged concentrically relative to the opening 23 and surrounds the same. Said shoulder 24 is provided with a plurality of faces 25 and 26 together forming ratchet teeth, as will be clear from Figs. 5 and 13. The faces 25 are inclined at an oblique angle to a plane parallel to the plane in which the bottom of the recess 23 lies and are relatively long, while the faces 26 are relatively short and are also inclined at an oblique angle to a plane parallel to the bottom wall of the recess 23, but in an opposite direction to the faces 25.

Mounted within the recess 23 is an insulating rotatable contact carrying member 27, preferably disk-like in shape. The wall portion 28 of the recess 23 is preferably of such a height and the thickness of the disk 27 is preferably such that when the parts are in position, the top face 29 of the disk-like member 27 will be substantially flush with the bottoms of the ratchet teeth formed on the shoulder 24. The disk-like contact carrying member 27 is shown more in detail in Figs. 6 and 7 and has mounted thereon a pair of similar bridging contacts 30. Said contacts are provided each with a pair of openings 31 arranged in spaced re-

lationship through which the leg portions 32 of the staples 33 extend. Said leg portions also extend through paired openings 31' in the member 27 aligning with the openings 31. The ends 34 thereof are clinched over as shown in Fig. 7 to firmly secure the contact members 30 in fixed position on the disk 27 due to the provision of the staples with the paired prongs or legs 32 and the paired openings in the contact and insulating members.

The contact members 30 are provided with contact making portions 35, 36, 37 and 38, said contact making portions being similar and projecting beyond the periphery of the disk-like insulating supporting member 27. The material of the disk-like member is cut away or notched, as indicated at 39, under each of said contact portions so as to provide for the proper flexibility of these parts. Said contact carrying member 27 is rotatable in only one direction, as will be described below, and the contact making portions 35, 36, 37 and 38 are all inclined, as will be clear from Figs. 6 and 7, so that the edges thereof lying on the forward side of said contacts when the device is rotating lie at the greater distance from the upper surface of the disk 27 than the rear portions thereof, thus giving a sort of camming action to the movable contacts whereby the same will always engage properly with the stationary contacts, which will be described below.

The rotatable contact carrying member 27 is further provided with an elongated opening 40 into which the flattened end portion 41 of a spindle 42 for rotating the member 27 extends. The end portion 41 of said spindle is provided with a pair of flat faces 43 that are adapted to engage with the flat faces 44 provided on the walls of the opening. The opening 40 is wider than the thickness of the end 41, and the walls 44 flare, thus allowing a slight amount of play between the spindle and the disk-like member 27 which facilitates the snap action of the switch. The outer end of the spindle 42 is provided with an enlarged cylindrical portion 45 which has a collar 46 thereon with which one end of the coil compression spring 47 engages, said spring surrounding the spindle 42 and engaging against an insulating washer 48 which is placed between the contacts 30 and the end of the spring to insulate said contacts from said spring. Said disk-like member 48 is provided with an elongated opening 49 for receiving the flattened portion 41 of the spindle 42.

Cooperating with the bridging contacts 30 of the movable contact carrying member 27 are the stationary contact members 50, 51, 52 and 53. The contacts 50, 52 and 53 are substantially alike, while the contact 51 is provided with an extension 54, the purpose

of which will be described below. Each of the contacts 50, 51, 52 and 53 is provided with an ear 55. Each of the ears 55 lies in a groove 56 in the insulating body portion 20 and is provided with a terminal portion 57 lying in a pocket or recess 58 in the insulating body portion 20. Each of the terminals 57 is provided with a sleeve-like or tubular portion 59 that rests in an opening 60 extending entirely through the insulating member 20 so that said terminals are accessible through the bottom or rear face of the member 20 for testing purposes, as will be clear from Fig. 10. The particular structure of the stationary contacts and terminals form the subject matter of a copending application by myself and Mr. Hans C. R. Popp, Serial No. 62,835, filed October 16, 1925.

20 The terminals associated with the contacts 50, 51, 52 and 53 have the conductors 61, 62, 63 and 64 secured thereto, respectively, by passing the bared ends thereof through the sleeve-like portions 59 and soldering the same in position by dipping or in any other manner, the solder being indicated in Fig. 10 by the numeral 65. The conductors 61, 62, 63 and 64 are each provided with the usual insulating covering 66, and while the same is shown as being broken away in the drawings to more clearly show the conductors within the same, yet this would not be the case in the actual construction of the device, as the same would be left with the ends merely cut off without being bared, as the baring thereof is unnecessary by providing the test openings 60 in the base member 20.

Each of the contacts 50, 52 and 53 are arranged to lie on one of the elongated inclined faces 25 of the ratchet teeth formed on the shoulder 24, these contacts being of substantially the same extent as said faces. The contact 51 rests not only on a face 25, but also has an extension 54 resting on an adjoining face 25 and the inclined connecting portion 67 lying against the face 26, spacing the faces 25. Thus, the contact 51 is in effect a continuous or double contact occupying two of the ratchet teeth. It will be noted that the contacts are arranged in a single series, each lying on similar faces of the ratchet teeth and that contacts rotatable in the same path engage therewith. Thus, the engaging portions of the stationary contacts are arranged in a single tier axially of the switch, as are also the movable contacts, which is desirable for the sake of simplicity and compactness. It is important that the contacts be arranged in a single tier so that the movable contacts successively engage with all of the same, no matter whether the same are all engaged by the same face of said movable contacts or otherwise.

The faces 26 are inclined at an oblique angle rather than at right angles to the bottom of the recess 23 as the gap between the adjoining contacts is thus increased, it being obvious that the distance along the inclined face 26 is greater than if a right angular face were provided. The projecting ends 35, 36, 37 and 38 of the contact members overlap the shoulder 24 and successively engage with the stationary contacts on said shoulder. This engagement is brought about by snap action due to the provision of the spring 47 which presses the member 27 into the recess 23 and holds the same properly yieldably seated therein and furthermore presses the ends of the contact members 30 against the inclined faces of the ratchet teeth. The rotation of the member 27 takes place in only one direction, due to the provision of the spring and the ratchet teeth, the ends of the contact members riding up the long inclined faces 25 of the teeth and dropping off the short inclined faces 26 thereof onto the next adjacent elongated inclined face 25 with a snap action due to both compression of the spring 47 and the provision of the play in the connection between the member 27 and the spindle 42, it being obvious that the member 27 will jump forwardly in a clockwise direction relative to the spindle a short distance when it reaches the top of the inclined face 26 so as to rapidly drop down the same. The spindle has operatively connected therewith an operating member 68, the particular connection between said members 68 and the spindle 42 forming the subject matter of a copending application by myself and Hans C. R. Popp, Serial No. 62,834, filed Oct. 16, 1925.

The cover plate 21 is secured to the insulating body portion 20 by means of suitable screws or other securing means 69 passing through the openings 70 in said member 20. The threaded boss 71 which may be in the form of a sleeve-like member having a flange 72 thereon brazed or otherwise secured to the flange portion 73 of the cover 21 extends outwardly from said cover member 21. The threaded member 71 is hollow, forming a tubular casing for the spindle 42 that is provided with a flange portion or shoulder 74 at the outer end thereof against which the flange 46 on the spindle engages, the spring 47 being thus held properly in compression. The threaded member 71 receives a threaded collar 75 by means of which the switch is clamped in position in the fixture. The threaded collar and the threaded portion 71 are such size relative to the operating member 68 that the switch mechanism can be removed and placed in position by merely removing the collar 75 over the member 68 without removing the member 68 from the switch. A second collar 90

may be threaded on the member 71 to lock the collar 75 in position if desired and the flange 73 may be provided with a plurality of ears 91 projecting outwardly therefrom with which the collar 75 is adapted to engage. The heads 92 of the securing member 69 may be seated in a suitable recess 93 as shown in Fig. 4. It will be noted that the terminal portions of the contact members are so mounted as to be housed between the insulating member 22 and the body portion 20 and held in position between the cover 21 and the member 20 due to the portions 55 being clamped between said parts.

In Fig. 9 an application of the switch to an electrical fixture is shown. The fixture is indicated by the numeral 76 and is in the form of a bracket having a pair of arms 77 and a body portion 78 which is provided with a suitable opening 79 through which the threaded member 71 passes, the switch as a whole being indicated by the numeral 80 and lying at the rear side of the body portion 78 with the operating member 68 only exposed to view from the front of the fixture. Obviously, it is very desirable to have a small compact switch for use in this position as the body portion 78 of the fixture is usually quite shallow. By the arrangement of the disk-like movable contact carrying member and the arrangement of the ratchet teeth in an annular series lying substantially parallel to the bottom or rear wall of the switch housing and the arrangement of the resilient means in the stem portion of the switch, the extreme compactness desirable is obtained. The lamps 81 and 82 are provided on the arms 77, suitable socket members 83 being provided for this purpose.

Referring now to Fig. 8 which diagrammatically shows the relationship of the switch mechanism to the lamps and to the line wires in order to obtain the connection of the lamps 81 and 82 either in series or in parallel, it will be seen that the line wires 84 and 85 are connected respectively with the stationary contacts 50 and 52 and that said terminals furthermore have connected thereto the conductors 86 and 87, each leading to one terminal respectively of the lamps 81 and 82. A suitable source of electric current is indicated in the diagram by the numeral 88. The actual connection of the conductors 86 and 84 and the conductors 85 and 87 respectively with the stationary contacts 52 and 50 is obtained through the conductors 61 and 63 extending from the switch mechanism, the three conductors 61, 85 and 87 being properly secured together in conducting relation at the ends thereof and the conductors 63, 84 and 86 being similarly secured together. In a similar manner, the conductors 62 and 64 are connected with the opposite terminals of the lamps 81 and 82 to those to which the conductors 86 and 87 are connected, said conductors 62 and 64 leading respectively to the contacts 51 and 53, the extension 54 being, of course, also connected with the conductor 62 and the lamp 82 due to the fact that the same is in electrical connection with the contact 51 by means of the connecting portion 67. The members 30 are diagrammatically indicated in Fig. 8, the ends thereof being indicated by the numerals by which the same are identified in Fig. 3.

In the position of the switch shown in full lines in Fig. 8, the contact portion formed by the end 36 is in engagement with the stationary contact 50 and the contact portion 35 is in contact with the stationary contact 53, while the contacting end 37 is in engagement with the contact 51 and the contacting end 38 with the contact 52. It will be clear that in this position of the switch the lamps 81 and 82 are connected in parallel or multiple relation with the source of current supply, the current passing from the wire 85 through the wire 87 to the lamp 82, back through the wire 62 and the contact member 30 engaging with the members 51 and 52 at 37 and 38 to the stationary contact 52 and then to the other line wire 84. Similarly, the current passes from the conductor 85 and the contact 50 through the end 36 of the other member 30 and by engagement of the end 35 with the contact 53 to the conductor 64, the lamp 81, the conductor 86 and to the contact 52 which is connected with the other line wire 84.

Upon rotation of the member 27 in a clockwise direction one-sixth of a revolution, the end 36 of the one member 30 engages with the contact 51, while the other end 35 thereof rests on the one face 25 of the ratchet teeth which has no stationary contact provided thereon and which serves as a dead contact. This entire member 30 is thus not included in the circuit when the movable contact member is in this position. The other member 30, however, has the end 37 thereof in engagement with the extension 54 of the contact 51 and the end 38 thereof in engagement with the contact 53, thus connecting the lamps 82 and 81 in series, the circuit being from the conductor 85 to the contact 50 through the conductor 87 to the lamp 82, then to the conductor 62, from this conductor 62 to the contact 51, then to the extension 54 which is in engagement with the end 37 of the member 30, the other end 38 thereof engaging with the contact 53, then from the contact 53 through the conductor 64 to the lamp 81 and from the lamp 81 through the conductor 86 to the contact 52 which is connected with the other line wire 84.

The next step by step movement of the member 27 in a clockwise direction brings the end 36 into engagement with the extension 54, the end 35 into engagement with

the contact 50, the end 37 into engagement with the contact 52 and the end 38 into engagement with the dead contact 25. This is one of the open circuit positions of the switch, the one bridging contact member 30 extending from the contact 52 to the dead contact 25 and the other bridging contact 30 extending from the contact 50 to the extension 54 of the contact 51 which merely shunts 10 around the lamp 82 without connecting the same with the other line wire 84.

The three positions described, the first of which is the full line position shown in Fig. 8, the second which is the dotted line position shown in Fig. 8, and the third of which is the dot and dash line position shown in Fig. 8, result from the rotation of the member 57 half-way around its complete cycle of movement. The connections are 20 then repeated except that the contact member 30 that has the projecting ends 35 and 36 now makes the connections previously made by the member having the projecting ends 37 and 38 and vice versa. In operation, when the full line position indicated in Fig. 8 is reached by the movable contact carrying member 27, the lamps 81 and 82 are brightly illuminated, being connected in parallel; when the next position of the movable contact carrying member is reached, the lamps 81 and 82 are dimmed due to the fact that they are connected in series; and when the following position to this is reached, the lamps 81 and 82 are both in open circuit 35 condition and extinguished.

It is particularly desirable to provide a switch of this character in a lighting fixture such as that shown or any other lighting fixture embodying a pair of lamps or two groups of lamps as two different steps of illumination can thus be obtained with substantially absolute uniformity of illumination from the two sources.

In Figs. 14 to 16 inclusive a modified form 45 of the invention is shown in which the insulating body portion is made up of an insulating disk 100 that is imperforate, a disk 101 of insulating material that is provided with suitable openings for the stationary 50 contacts and for receiving the ends of the conductors leading into the switch mechanism, a disk-like member 120 corresponding to the member 20 in Figs. 1 to 13 inclusive, a cover plate 121 and an insulating gasket 55 122. The member 121 is provided with ears 102 that are clinched over the member 100 at 103 to hold the parts in assembled position. Said member 121 is provided with a tubular threaded extension 171 corresponding 60 to the member 71 in Figs. 1 to 13 inclusive through which an operating spindle 142 extends which is rotated by means of the operating member 168.

Mounted within the member 101 in suitable recesses 65 158 are the terminals 157 pro-

vided on the conductors 161, 162, 163, and 164 corresponding to the conductors 61, 62, 63, and 64 shown in Fig. 3.

The member 120 is provided with an opening 123, the side wall of which is provided 70 with arcuate faces 104 alternating with flat faces 105, said flat faces being offset from the arcuate faces 104 at 106 and 107, the offsets 106 being deeper than the offset 107, the offset 107 being merely deep enough so 75 that the contacts 150, 151, 152 and 153 respectively on the terminal 157 mounted on the conductors 161, 162, 163, and 164 are seated substantially flush with the arcuate faces 104 at the shoulders 107. A contact 80 154 is mounted in a similar manner and is provided with an extension 108 that interlies the terminal 157 having the contact 151 thereon thus being electrically connected with the contact 151 and being in effect an 85 extension thereof. The contacts 150, 151, 152, 153, and 154 correspond to the contacts 50, 51, 52, 53, and 54 in the form shown in Figs. 1 to 13 inclusive.

The shaft or spindle 142 is provided with a flattened head 109 and with a circular projection or boss 110 thereon which enters the opening 111 in the bottom 112 of the member 120 to act as a bearing for the spindle 142. The flattened portion 109 of the spindle 142 is provided with a pair of slots 113 in which the S-shaped contact members 130 are mounted, the ends 114 of said members 130 engaging with the contacts 150, 151, 152, 153, and 154 with a wiping action and engaging yieldingly therewith due to the resiliency of said contact members 130. Upon rotation of the member 142 in a clockwise direction, the contacts 130 bridge the contacts 152 and 151, and the contacts 153 and 150 to connect the electrical devices in parallel and in the next position bridging the contacts 154 and 153 to connect the same in series and assuming the position shown in full lines in Fig. 16 when the circuit is broken. As said members 130 rotate, they will move along on the arcuate faces 104 and drop off the shoulders 106 to engage with the contacts 150 to 154 with a snap action. The member 105', which is the dead contact in this form, is provided with only one shoulder 106 while the opposite end of said face terminates flush with the adjoining curved face 104.

While the principle of operation of the switch shown in Figs. 14 to 16 inclusive is substantially the same as that shown in Figs. 1 to 13, the arrangement is not as desirable from a practical standpoint because the switch is not as compact and is not as reliable in operation as in the form shown in Figs. 1 to 13 inclusive.

Having thus described my invention, what I desire to claim and secure by U. S. Letters 120 Patent is:

1. In a device of the character described, a rotatable contact carrying member, a plurality of stationary contacts, comprising a pair of contacts serving as terminals of an input circuit, one of said contacts serving as one terminal of one output circuit and the other contact serving as one terminal of another output circuit, and a pair of contacts serving each respectively as the other terminal of the respective output circuits and a pair of contacts on said rotatable contact carrying member connecting each of said combined input and output circuit terminal contacts with one of said output circuit terminal contacts for one position of said rotatable member and connecting said output circuit contacts directly with each other for another position of said rotatable member.
2. In a device of the character described, a plurality of stationary contacts adapted to have a source of current supply connected therewith, a plurality of stationary contacts each adapted to have an electrical device connected therewith, a rotatable member having contacts engaging with said stationary contacts by snap action to connect said electrical devices with said source of current supply either in series or in parallel and means for rotating said rotatable member step by step in the same direction.
3. In a device of the character described, an insulating body portion, having a recess therein, a movable contact carrying member of insulating material seated for rotation in said recess, a pair of contact arms on said member each having opposite ends projecting laterally outwardly therefrom beyond the periphery of said recess and contacts on said body portion adjacent said recess cooperating with said ends of said contact arms.
4. In a device of the character described, an insulating body portion having a recess therein, a shouldered portion provided with ratchet teeth adjacent said recess and surrounding the same and extending outwardly therebeyond, a movable contact carrying member rotatably mounted in said recess, stationary contacts on said shouldered portion, contact means on said movable contact carrying member and resilient means for yieldably holding said contact means in engagement with said ratchet teeth and said stationary contacts.
5. In a device of the character described, an insulating body portion having a recess therein, an annular shoulder surrounding said recess having faces providing ratchet teeth, stationary contacts having portions overlying certain of said faces, an insulating member rotatably mounted in said recess, bridging contacts on said rotatable insulating member insulated from each other and having ends projecting over said shoulder and resilient means for yieldably holding said bridging contacts in engagement with said ratchet teeth and said stationary contacts.
6. In a device of the character described, an insulating body portion having a recess therein, an annular shoulder surrounding said recess having faces providing ratchet teeth, stationary contacts having portions overlying certain of said faces, an insulating member rotatably mounted in said recess, a pair of bridging contacts lying on opposite sides of the axis of and secured to one face of said rotatable insulating member having ends projecting over said shoulder and resilient means for yieldably holding said bridging contacts in engagement with said ratchet teeth and said stationary contacts.
7. In a device of the character described, an insulating body portion having a recess therein, an annular shoulder surrounding said recess having faces providing ratchet teeth, stationary contacts having portions overlying certain of said faces, and terminal portions lying outwardly of said shoulder and rotatable contact means cooperating with said stationary contacts, one of said stationary contacts overlying a plurality of said faces.
8. In a device of the character described, an insulating body portion having a substantially circular recess therein, stationary contacts mounted thereon outside the rim of said recess, a disk of insulating material seated and rotatable in said recess and a pair of bridging contact members secured to one face of said disk, said bridging contacts being insulated from each other and having free ends projecting beyond the edge of said disk.
9. In a device of the character described, an insulating body portion having a substantially circular recess therein, stationary contacts mounted thereon, a disk of insulating material seated and rotatable in said recess and a pair of bridging contact members secured to one face of said disk, said bridging contacts being insulated from each other and having free ends projecting beyond the edge of said disk, said disk having cut-away portions under said contacts adjacent the ends thereof.
10. In a device of the character described, an insulating body portion having a substantially circular recess therein, stationary contacts mounted thereon outside the rim of said recess, a disk of insulating material seated and rotatable in said recess, a pair of bridging contact members, means for securing each of said bridging contact members to said disk at spaced points, said bridging contacts being spaced to insulate the same from each other, and each having both end portions projecting beyond the rim of said recess to engage said stationary contacts.
11. In a device of the character described,

- an insulating body portion having a substantially circular recess therein, stationary contacts mounted thereon, a disk of insulating material seated and rotatable in said recess, 5 a pair of bridging contact members, a staple for securing each of said bridging contact members to said disk at spaced points, said bridging contacts being spaced to insulate the same from each other.
- 10 12. In a device of the character described, an insulating base member having a recess therein, an insulating disk rotatably mounted therein, contacts on said base member, and said disk, said disk having a central oblong opening therein, and an operating spindle having an end provided with flattened faces seated in said opening.
- 15 13. In a device of the character described, an insulating base member having a recess therein, an insulating contact supporting member rotatably mounted therein, contacts on said base member and said contact supporting member, said contact supporting member having a central oblong opening therein, an operating spindle having an end provided with flattened faces seated in said opening, and resilient means surrounding said spindle to yieldingly hold said contact supporting member in said recess.
- 20 14. In a device of the character described, an insulating base member having a recess therein, an insulating contact supporting member rotatably mounted therein, contacts on said base member and said contact supporting member, said contact supporting member having a central oblong opening therein, an operating spindle having an end provided with flattened faces seated in said opening, resilient means surrounding said spindle to yieldingly hold said contact supporting member in said recess, and an insulating washer between said resilient means and said contact supporting member.
- 25 15. In a device of the character described, an insulating member having a recess in one face thereof, an annular shoulder concentric with said recess and an annular series of ratchet teeth formed in the top face thereof, said ratchet teeth having alternating inclined elongated faces and inclined short faces connecting said elongated faces.
- 30 16. In a device of the character described, an insulating member having a recess in one face thereof, an annular shoulder concentric with said recess and an annular series of ratchet teeth formed in the top face thereof, said ratchet teeth having alternating inclined elongated faces and inclined short faces connecting said elongated faces and 35 stationary contacts having portions resting on certain of said elongated faces.
- 35 17. In a device for connecting a pair of electric lights with a source of current either in series or parallel arrangement, snap action means including movable contacts,
- 40 and a plurality of stationary contact elements having engaging faces all lying substantially in a single annular tier, an insulating support for said movable contacts and spring means urging said support in a direction axially of said tier to force said movable contacts against said stationary contacts.
- 45 18. In a device of the character described, a switch body portion, movable contact means mounted to assume a plurality of definite predetermined positions relative to said body portion, an annular series of stationary contacts mounted so as to occupy positions corresponding to certain of the 50 positions of said movable contact means, one of said stationary contacts occupying a plurality of said positions, and means for moving said movable contact means into each of its positions with a snap action, said movable contact means comprising a pair of bridging contacts lying in substantially the same plane and insulated from each other.
- 55 19. In a device of the character described, a switch body portion, movable contact means mounted to assume a plurality of definite predetermined positions relative to said body portion, a plurality of terminals, contact portions cooperating with said movable contact means electrically connected with 60 said terminals, said contact portions being arranged in a single tier, each of said contact portions mounted so as to occupy a position corresponding to a position of said movable contact means, a pair of contact portions in 65 engagement with said movable contact means in two successive positions thereof being connected with a single terminal and means for moving said movable contact means into each of its positions by snap action, said movable contact means comprising a pair of bridging contact members insulated from each other and each engageable with each contact portion.
- 70 20. In a device of the character described, an insulating body portion having faces thereon providing a series of ratchet teeth, movable contact means rotatable step by step into position opposite alternating faces on 75 said teeth, and contact means having portions overlying a plurality of said alternating faces, the contact means on two succeeding alternating faces being electrically connected together.
- 80 21. In a device of the character described, an insulating body portion having faces thereon providing a series of ratchet teeth, movable contact means rotatable step by step into position opposite alternating faces on 85 said teeth, and contact means having portions overlying a plurality of said alternating faces, the contact means on two succeeding alternating faces being electrically connected together, and one of said alternating faces having no contact means thereon.

22. In a device of the character described, an insulating body portion having faces thereon providing a series of ratchet teeth, movable contact means rotatable step by step 5 into position opposite alternating faces on said teeth, and contact means having portions overlying a plurality of said alternating faces, the contact means on two succeeding alternating faces being electrically connected together, and one of said alternating faces having no contact means thereon, said last mentioned face lying substantially opposite one of said electrically connected contact portions.
23. In a device of the character described, an insulating body portion provided with a plurality of ratchet faces, stationary contacts mounted on certain of said ratchet faces and a movable contact member having 20 a pair of yieldable bridging contacts insulated from each other mounted thereon cooperating with said stationary contacts, either end of each of said bridging contacts being engageable with each of said stationary contacts.
24. A device of the character described having a plurality of circumferentially ar- ranged relatively stationary contacts serving respectively as circuit terminals for a source of current supply and for two translating device circuits, and two bridging contacts insulated one from the other rotatable step by step in the same direction into selected relationship to said stationary contacts to selectively connect said translating 35 device circuits in series or parallel or open circuit relationship to said source of current.
25. In a device of the character described the combination of a plurality of stationary contacts, two rotatable bridging contacts insulatingly mounted one from the other, circuit terminals for a source of power, circuit terminals for two translating device circuits, and interconnections, the latter three elements being associated with said contacts to 40 permit a series-parallel control of said translating device circuit terminals, and a single hill and valley runway for said rotatable contacts whereby a snap-action movement thereof is secured.

In witness whereof, I hereunto subscribe my name this 7th day of October A. D., 1925.

VICTOR R. DESPARD.
